UNITED STATES PATENT OFFICE.

GEORGE B. OWEN, OF WINSTED, CONNECTICUT.

DESIGN FOR CLOCK-DIAL RIMS.

Specification forming part of Design No. **11,474**, dated October 28, 1879; application filed September 19, 1879.
[Term of patent 7 years.]

To all whom it may concern:

Be it known that I, GEORGE B. OWEN, of Winsted, in the county of Litchfield and State of Connecticut, have invented a new and Improved Design for Clock-Dial Rims, of which the following is a specification.

My design relates specifically to the ornamentation of the metal rim surrounding the clock face or dial.

A is the annular rim, made of metal, having on its front a circle or wreath of leaves, B. From the lower side of the rim depends a draped curtain, C, which is caught up and looped to the center immediately under the crown B, and tied with cord and tassels.

Having thus described my invention, I claim

as new and desire to secure by Letters Patent—

1. As an ornamental design for metal rims for clock dials or faces, a draped and looped curtain depending from the under side of the rim, substantially as shown and described.

2. An ornamental design for the metal rims of clock faces or dials, composed of a circle or wreath of leaves on the face of the rim, and a draped and looped curtain depending from the rim under the circle or wreath of leaves, substantially as herein shown and described.

GEO. B. OWEN.
